DESIGN FOR A CARPET.

SPECIFICATION forming part of **Design No. 20,617**, dated **March 24, 1891**.

Application filed **February 7, 1891**. Serial No. **380,662**. Term of patent **3½ years**.

To all whom it may concern:

Be it known that I, PAUL PIGNOT, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design is composed of the body A and the border B. The body A consists of groups of flower and leaf forms somewhat resembling the iris and rose upon a shaded ground of

curved and scroll-shaped ornaments. The border B has an inner ornamental margin, a band consisting of groups of flower and leaf forms somewhat resembling the iris and rose, and an outer ornamental margin.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.
